SAFETY RAZOR

Martin Glaberson, Ardsley, N.Y., assignor to Warner-Lambert Company, Morris Plains, N.J.

Continuation-in-part of abandoned design application Ser. No. 191,958, Oct. 22, 1971. This application May 3, 1972, Ser. No. 250,100

Term of patent 14 years

Int. Cl. D28—03

U.S. Cl. D95—3 A

Fig. 2

Fig. 4

Fig. 1

FIG. 5

FIG. 6

FIG. 7

FIG. 1 is a perspective view of a safety razor showing my new design;

FIG. 2 is a side elevational view thereof;

FIG. 3 is a front elevational view thereof;

FIG. 4 is a rear elevational view thereof;

FIG. 5 is a front view of an upper portion thereof taken along the arrow of FIG. 2;

FIG. 6 is a top plan view thereof; and

FIG. 7 is a bottom plan view thereof.

The side not shown is a mirror image of FIG. 2.

This application is a continuation-in-part of design application Ser. No. 191,958 for Razor With Blades Bonded In A Disposable Cartridge, filed Oct. 22, 1971 and now abandoned.

I claim:

The ornamental design for a safety razor, as shown and described.
